United States Patent Office

Des. 191,889

Patented Dec. 5, 1961

191,889

COMPRESSOR

Robert W. Hyde, Cincinnati, Ohio, assignor to Superior Tool and Grinding Co., House Springs, Mo., a corporation of Missouri

Filed July 13, 1961, Ser. No. 65,915

Term of patent 14 years

(Cl. D65—1)

Fig. 3

FIGURE 1 is a front elevational view of a compressor embodying the present design.

FIGURE 2 is a rear elevational view of the present compressor.

FIGURE 3 is a top plan view of the present compressor.

FIGURE 4 is a side elevational view of the present compressor.

FIGURE 5 is an elevational view of the opposite side of the compressor.

I claim:

The ornamental design for a compressor, substantially as shown.
